UNITED STATES PATENT OFFICE

2,205,753

SHOE

Paul Svrilinga, Jr., Chicago, Ill.

Application June 6, 1939, Serial No. 277,635

4 Claims.

(Cl. 36—3)

This invention relates to an improvement in shoe construction, one of the main objects being the provision of means whereby the shoe will be adapted to accommodate a height extension insert, which will enable the wearer to appear taller. For people of short stature this is a much needed improvement.

Another object of the invention is the provision of a height extension member attached to a shoe, which will also provide a means of ventilation to the foot of a wearer.

A further object of the invention is the provision of an insert for extending the height, or increasing the stature of a wearer, which at the same time will provide additional comfort to the arch of the foot, and which is attached permanently to the shoe by means of grommets or other similar means of attachment.

A further object of the invention is to provide a device for the purpose stated which is efficient, practical, useful, and economical to manufacture in quantity production.

Other objects of the invention will become apparent by reference to the accompanying drawing and the ensuing description wherein like symbols are utilized to designate like parts and in which;

Fig. 1 is a side view of a shoe in accordance with the features embodied in my invention; this view is partly shown in cross-section in order to clearly depict the important structural elements of my invention.

Fig. 2 is a transverse cross-sectional view on the line 2—2 of Figure 1.

Fig. 3 is a fragmentary transversal cross-sectional view on the line 3—3 of Figure 1.

Fig. 4 is another form of my invention showing the method employed when it is desired to construct my invention of cast or plastic materials. This view is taken on the line 4—4 of Figure 5.

Fig. 5 is a cross-sectional view on the line 5—5 of Figure 4.

Referring further to the drawing, it will be seen in Figure 1, that the illustration shows the foot of a wearer generally designated by the numeral 28 and inserted into a shoe of the form comprising my invention, the shoe is generally designated by the numeral 6, and is provided with a sole and a standard heel designated by the numeral 7 attached thereto.

The rear portion of the upper part of the shoe which fits the foot generally designated by the numeral 16, is provided with a deeper cut-out portion than is standard practice and is designated by the numeral 17.

Now in order to adapt the shoe to the purpose and utility for which my invention has been conceived, the portion 16 or the rear portion of the upper part of the shoe, is somewhat extended in height sufficiently to enable the insert designated by the numeral 11 to be accommodated therein, and also to accommodate the heel portion of the foot of a wearer for the reason that a standard shoe is not adapted to accommodate the inserted piece designated by the numeral 11.

These changes from the normal shape of the shoe should be made to work in nicely with the rest of the dimensions so as to maintain a pleasing proportion.

The portion 16 will have to be, somewhat, built up or extended in height in order to accommodate this structure, and for this reason the upper arcuate portion designated by the numeral 17 must be cut deeper than it would be cut on the upper part of the average shoe in order that it furnish ample clearance for the ankle of the foot.

The important elemental structure of my invention resides primarily in the piece or member designated by the numeral 11. As can be seen in Figure 1, the member 11 has a top surface designated by the numeral 14 which is made configuratively and congruently with the shape of the sole of the foot toward the heel portion and also to fit partly the contour of the arch of the foot.

The lower portion 15 on the member 11 is made to conform to the rear portion inner sole and arch of the shoe. As can be noticed, the under portion of the member 11 is slightly recessed as designated by the numeral 19, the relieved surface being designated by the numeral 13 (Figure 2), the reason for this recessed portion is twofold, one is that it eliminates the necessity for accurate fitting of the shoe to the lower portion of the member 11, and secondly that it will provide a by-pass for ventilation to be circulated to the front portion of the foot. This will become more apparent further along in this specification.

The member 11, as can be noticed, is provided with a counter-sunk recess or counter-bore designated by the numeral 12 and the heel portion is provided with a similar counterbore designated by the numeral 8. The grommets designated by the numeral 9 are used to fasten the member 11 to the shoe in the manner illustrated; the end of the same are spun over to abut the top and bottom counter-bores respectively designated by the numerals 12 and 8, in order to hold the member 11 definitely and fixedly in place in the shoe.

The member 11 as indicated in Figure 2, is

made up of very light weight material, like balsa wood which would be the ideal material for this purpose. It is a well known fact that balsa wood is a very light wood, hence the member 11 would not, perceptibly, add to the weight of the shoe thereby making for the most ideal possible arrangement.

Particular stress is laid on the fact that the member 11 is made of a solid material rather than a resilient or compressible material, so that the dimension of the member 11 namely the height dimension toward the rear or its thickness would definitely determine the amount of increase in stature it will provide to an individual wearing a shoe equipped with the same.

The grommets are provided with a series of holes designated by the numeral 18 which provide a means of communication for the air drawn in thru the grommets and dispersed thru the channel designated by the numeral 19 being further distributed to the inner part of the shoe.

Figure 3 shows a view of the shoe cut in transversal section and indicates more clearly the method of securing the member 11 to the shoe. The member 11 may also be secured by nails or screws or any other means when it is not desired to provide ventilation to the foot.

In Figures 4 and 5, I show a slightly modified form of my invention, the structure being the same shape as the member 11 except that it is made of a light metal or perhaps a molded product like Bakelite, and for that reason it is made of a rather light cross-section as indicated by the views Figure 4 and Figure 5.

The alternate form illustrated in Figures 4 and 5 is generally designated by the numeral 18, and is comprised of a top surface 20 which is made configurative with the heel portion and the arch portion of the foot adjoining the heel portion, and is provided with a lower surface designated by the numeral 22 which is configurative with the shape of the rearward inner portion of the sole of a shoe.

It is also provided with a relieved surface designated by the numeral 21, thus eliminating the need for accurate fit to the sole of a shoe, at the same time providing a passage for passing air or ventilation to the sole of the foot similarly as indicated, illustrated, and explained with respect to the form shown and illustrated in Figures 1 and 2.

The member illustrated in Figures 4 and 5 generally designated 18, is provided further with two recesses or cavities 25 in order to make the member 18 as light weight as possible; the reinforcement rib designated by the numeral 26 giving the entire affair strength and rigidity.

The side portions are open, and slightly tapered as indicated at 27, the numeral 23 designates openings at the rear end, and at the side, since the top portion 20 and the portion 21 are held together by the rib 28. The hole designated by the numeral 24 is provided in order to facilitate holding the cores for the spaces 25 when the casting is made, otherwise this hole has no particular significance in the invention at bar.

The shoe as constructed with my invention, will provide a means of increasing the stature of an individual. Of course it is understood that both members 11 or 18 are made of solid material non-resilient and non-compressible so that whatever their distance or height may be, it will be equivalent to the height that will

be added to the wearer, thus increasing his stature.

In spite of the fact that the standard shoe has to be modified somewhat in dimension, it will not be readily apparent to the average observer and a person wearing the shoe with my invention, will appear the same as if he wore shoes normally constructed.

Of course, this same purpose has been accomplished by increasing the height of the shoe heel, which method is not as desirable because it attracts attention to the wearer, and points out the fact that he is, normally, short in stature. With my invention, the wearer's stature is increased without anyone, but the wearer actually knowing it to be so.

I believe, I have described my invention succinctly, and inasmuch as it is susceptible of many modifications, changes, and alterations, I reserve the right to all such changes, modifications, and alterations, which may come within the scope of the spirit of my invention.

Having thus described and revealed my invention what I claim as new and desire to secure by Letters Patent is:

1. In a shoe structure, a height extending member made of a solid material secured to said shoe, the said height extending member provided with a ventilating recess at its lower surface, grommet means provided with ventilating holes adapted to register with the ventilating recess in said lower surface and further adapted to secure the said height extending member to the said shoe.

2. In a shoe structure, a height extending member made of moldable material secured to said shoe, the said height extending member provided with a top portion configurative with the shape of the heel and arch of a human foot member, and a lower portion configurative with the shape of the rearward portion of the inner sole and arch of said shoe, the said top portion being joined to the said lower portion by an arcuately tapered rib portion, the said lower portion provided with a ventilating recess, and grommet means provided with ventilating holes adapted to register with the ventilating recess in said lower portion and further adapted to secure the said height extending member to the said shoe.

3. A shoe structure comprising a sole, heel and upper portion, having attached thereto a height extending member made of moldable material, the said height extending member comprising a top portion configurative with the shape of the heel and arch of a human foot member, and a lower portion configurative with the shape of the rearward portion of the inner sole and arch of said shoe, the said top portion being joined to the said lower portion, by an arcuately tapered rib portion, the said lower portion provided with a ventilating recess, and grommet means provided with ventilating holes adapted to register with the ventilating recess in said lower portion and further adapted to secure the said height extending member to the said shoe.

4. In a shoe structure, height extending means provided with ventilating means, and grommet means provided with ventilating holes adapted to register with the ventilating means in said height extending means and further adapted to secure the said height extending means to the said shoe.
